MACHINE TOOL

Maxwell I. Mathewson, Providence, R. I., assignor
to Brown and Sharpe Manufacturing Company,
a corporation of Rhode Island

Application August 3, 1940, Serial No. 350,359

11 Claims. (Cl. 51—95)

The present invention relates to improvements in machine tools, and is concerned more particularly with the organization of a rotary work supporting assembly particularly adapted for use in a grinding machine which includes specifically a work table, and a headstock and footstock mounted thereon.

It is one object of the invention to provide a work supporting assembly including a work table, a headstock and a footstock adapted for use in a grinding machine, of which the headstock and footstock are constructed and arranged to be readily interchangeable on the table so that the headstock may be located at one side or the other of the grinding wheel in accordance with the requirements of the particular work, as for example in shoulder grinding, to avoid interference of the headstock with the grinding wheel carriage and associated parts.

Other objects of the invention relate more specifically to the improvement of the several associated devices comprising a work supporting assembly of this general description.

With these and other objects in view as may hereinafter appear, a feature of the invention consists in the provision of a work supporting assembly including a work table with a headstock and a footstock supported thereon, each of the headstock and footstock being mounted on swivel mountings on the table ways, and having their centering spindles respectively passing through the axis of the swivel mounting so that the headstock and footstock may be readily interchanged to permit reversal in the position of the work on the table.

Another feature of the invention consists in the provision in a work supporting assembly of this general description including a headstock having a headstock motor mounted integrally therewith, of driving connections for the headstock motor which include a flexible cable and plug attachable at either end of the table to directional motor driving electrical outlets whereby the direction of rotation of the motor is automatically determined in accordance with the position of the headstock at the left or right hand end of the table through the attachment of the flexible cable and plug into the corresponding electrical outlet.

Another feature of the invention consists in the provision in a grinding machine having a work supporting assembly of this general description including an interchangeable headstock and footstock, of a footstock spindle operating lever, and supporting means for the lever on which the lever is shiftable from one operating position to

another to cause the lever always to be located on the side of the footstock facing the operator, regardless of the direction in which the footstock faces at the left or the right hand end of the work table.

Another feature of the invention consists more specifically in the construction and arrangement of the footstock including a centering spindle adapted for supporting footstock type diamond tool holders constructed and arranged to be mounted in two alternative positions enabling a single diamond tool holder to be employed and to be set at the correct operating angle for alternative positions of the footstock at either the left or right hand end of the table.

The several features of the invention consist also in the devices, combinations and arrangement of parts hereinafter described and claimed, which together with the advantages to be obtained thereby will be readily understood by one skilled in the art from the following description taken in connection with the accompanying drawings, in which Fig. 1 is a view in rear elevation of a grinding machine, only so much of the machine being disclosed as is believed necessary to illustrate the connection of the present invention therewith; Fig. 2 is a view in rear elevation similar to Fig. 1, but with the headstock and footstock in their reversed positions; Fig. 3 is a view in right side elevation of the machine, that is, looking from the left of Fig. 2; Fig. 4 is a wiring diagram showing particularly the electrical connections including the receptacles at the right and left side of the machine for controlling the direction of the headstock motor in its alternative operating positions; Fig. 5 is an end view of the footstock looking from the left of Fig. 6; Fig. 6 is a view in front elevation of the centering spindle as shown in Fig. 5, with a portion of the frame broken away to show the underlying parts; Fig. 7 is a detail sectional view taken on the line 7—7 of Fig. 6; Fig. 8 is a sectional view taken on the line 8—8 of Fig. 6; and Fig. 9 is a detail sectional view taken on the line 9—9 of Fig. 6.

The grinding machine disclosed in the drawings as embodying in a preferred form the several features of the invention, comprises a base support 10, a table support 12 mounted to slide on ways 14 on the base 10, and a grinding wheel spindle carriage 16 slidably supported in ways in a swivel mounting 18 on the base 10. As generally indicated in Fig. 3 of the drawings, a grinding wheel 20 is supported at one end of a grinding wheel spindle 22, the other end of which carries a pulley 24 driven by means of a belt 26 and pulley

28 on the armature shaft of an electric motor 30.

The work supporting assembly of the machine comprises with the table support 14, a headstock 32 and a footstock 34 which with the present construction are carried respectively on swivel mountings 36 and 38 adjustably supported on a swivel table 40 on the table 12. As best shown in Fig. 3 of the drawings, the headstock 32 is provided with a center 42 and a work driving plate which is driven by means of a belt and pulley drive generally designated in dotted lines in Fig. 3, from an electric motor 44 mounted in the headstock. The table 40 comprises a pair of positioning surfaces 46 and 48 which lie respectively in a horizontal and a vertical plane, and are constructed with a high degree of precision to insure the accurate location of headstock and footstock on the work table. Correspondingly shaped surfaces of the swivel support 36 are held firmly in engagement with the table by means of clamping screws 50 which extend downwardly at an angle through the swivel mounting 36, and at their lower ends are provided with enlarged heads which engage within a T-shaped slot 52 in the table 40. The center 42 is arranged to extend through the axis of rotation of the headstock on its swivel mounting, so that the headstock will always be located in the identical position transversely of the table independently of whether the headstock is located at one end of the table facing left as shown in Fig. 1, or at the other end of the table facing right as shown in Fig. 2.

In accordance with the usual practice in machines of this type, the grinding wheel 20 rotates in a direction which will cause the peripheral abrading surface to move downwardly against the work. The headstock is arranged to rotate the work in an opposite direction in which the engaged peripheral surface of the work is moving upwardly against the grinding wheel. In accordance with a feature of the present invention, means are provided to insure the rotation of the work in the proper direction for each of the alternative reversed positions of the headstock and footstock as represented in Figs. 1 and 2. For this purpose, a three phase headstock motor is employed, the direction of rotation of which is determined by the order in which the three phase lines are connected to the motor. The motor is driven from a main three phase power line in the base of the machine, and terminates in two directional outlets 54 and 56 located at opposite ends of the table and arranged to receive a plug 58 on a flexible electric cable 60 through which power is transmitted to the headstock motor 32. The outlets 54 and 56 are so arranged that the plugging of the plug 58 and electric cable 60 into the outlet 54 as shown in Fig. 1, will cause the headstock motor 44 to be rotated in one direction as designated by the arrow, whereas, plugging the cable 58 into the outlet 56 will cause the headstock motor 44 to rotate in the opposite direction in accordance with the illustration in Fig. 2.

The electrical driving connections for the machine are shown in greater detail in Fig. 4 of the drawings. Power is supplied by a three phase power line L¹, L² and L³. The current is then transmitted through a secondary line T31, T32 and T33 to each of the outlets 54 and 56. As clearly shown in Fig. 4, the outlets 54, 56 are each provided with one large socket and three small sockets which are arranged to engage with correspondingly placed prongs of the plug 58. It will also be evident from an inspection of the electrical diagram Fig. 4, that the phase lines T32 and T33 are reversed with respect to one an-

other in the outlets 54, 56, so that the transfer of the plug 58 from one or the other of these outlets will act to reverse the direction of rotation of the headstock motor 44.

5 The footstock 34 with its swivel mounting 38 is adjustably secured to the table 40 by means of clamping screws 64 which extend downwardly at an angle through the swivel mounting 38, and are provided at their lower ends with enlarged 10 heads engaging within the T-shaped slot 52 extending along the length of the table ways. The footstock is provided with a tapered dead center 66 which is fitted into a footstock spindle 68 adjustably supported within a housing 70 having 15 a manually operable clamping screw 71 and associated clamping blocks 69. The construction and arrangement of the footstock is such that the center line of the center 66 and spindle 68 passes transversely through the axis of rotation of the 20 footstock 34 on its swivel mounting 38, so that reversal of the position of the footstock on the table guideway will not alter the position of the line of centers of the work.

In accordance with the usual practice, the footstock spindle 68 is arranged to be shifted axially into and out of work engaging position by means of mechanism which is adapted for engaging the footstock center 66 against the work under a predetermined spring pressure before the clamp 71 is tightened to lock the footstock in position. Means is also provided for producing a fine adjustment of the footstock spindle 68 and center 66 axially with respect to its actuating mechanism.

35 As best shown in Fig. 8 of the drawings, the spindle 68 has screw-threaded into the rear end thereof an adjusting screw-threaded shaft 72 which carries at its outer end a hand wheel 73. The shaft 72 is rotatably supported within a 40 sleeve 74 which engages at one end against the sleeve hub of the hand wheel 73 and at its other end against a collar 75 on the shaft 72. In the present construction the sleeve 74 is slidably supported and is keyed to turn with a sleeve member 76 which is in turn externally supported for rotational movement within a split clamp bearing 78 in the footstock 34. As best shown in Figs. 7 and 8, the clamping screw 80 of this bearing is arranged to engage in an annular groove 82 extending half way around the circumference of the sleeve member 76, thus locking the sleeve member 76 against axial movement while permitting a limited rotational movement of the sleeve member 76 whenever clamping pressure of the split clamp 78 is eased by backing off the clamping screw 80. 45 The sleeve member 76 serves as a housing for the actuating mechanism above mentioned for advancing and retracting the footstock spindle 68. This actuating mechanism comprises a manually operable control lever 84 and a pair of compression spring-pressed plungers 85 which act on the control lever 84 in a direction to maintain the spindle 68 and center 66 yieldingly in an extreme 50 forward position determined by the engagement of the shoulder on the sleeve 74 with the rear face of the sleeve member 76. The hand lever 84 is supported on a pivot pin 86 carried on two 55 rearwardly extending lugs 88 on the sleeve member 76. An extension 90 of the lever 84 engages within a socket 92 in the sleeve 74 to provide an operative connection between the lever and the footstock spindle. Two arms 94 extending from the hub portion of the lever 84 engage against the spring-pressed plungers 85 which tend to 60 swing the lever 84 in a counter-clockwise direction.

tion as shown in Fig. 8, to maintain the spindle in its forward position. In order to permit the locking of the footstock in a fully retracted position against the pressure of the plungers 85, a radially extending detent 98 is provided in the sleeve member 76 which can be shifted inwardly into locking engagement with a recess 100 in the sleeve 74 when the sleeve 74 and spindle connected therewith have been moved to their fully retracted position.

In accordance with one feature of the invention, the footstock is particularly constructed and arranged so that the hand lever 84 may be readily shifted from one side to the other of the headstock in order to place this element in the most accessible position for the operator, depending on whether the headstock is located in one or the other of its reverse positions at opposite ends of the table. With the construction above illustrated and described, the hand lever 84 may be readily shifted from one side to the other of the headstock by merely loosening the clamping screw 80, and thereafter by turning the entire assembly including the lever 84, the supporting sleeve member 76 with the sleeve 74 through 180° to the alternative limiting position which is determined by the engagement of the clamping screw 80 with the opposite end of the locking groove 82. The screw 80 is then again tightened up to lock the parts in their adjusted position.

Another feature of the present invention consists in the construction and arrangement of the footstock to enable a footstock type diamond tool holder for grinding wheel truing to be located in a proper position of adjustment for each of the reverse operating positions of the footstock at opposite ends of the table. As best shown in Figs. 5 and 6 of the drawings, the truing tool holder comprises a holder 104 within which is supported a diamond tool 106. The holder 104 is formed with a bearing surface 108 which engages the upper side of the dead center 66 and a semi-circular downward extension having a clamping screw 110 which is tightened against the opposite side of the center 66. An upward extension of the holder 104 is journaled to receive a forwardly extending positioning pin 112 rigidly located on the footstock. The pin 112 is secured in an upwardly extending arm of a bracket 114 which is rigidly secured to the forward end of the spindle 68, and serves also to provide a dust guard for the spindle bearing. A set screw 116 on the bracket 114 serves to secure the pin 112 in position in the bracket. A set screw 117 provided in the holder 104 serves to secure the holder to the positioning pin 112. It will be noted that the positioning pin 112 is located at one side of a vertical plane passing through the axis of the foot stock spindle 68 and the center 66. This offset is required to provide a clearance for the positioning pin 112 and the upper portion of the truing tool holder 104, supported thereby during the truing operation.

When the footstock is shifted from the position of Figs. 1, 5 and 6 to its reverse position at the opposite end of the table, as shown in Fig. 2, it is required also to reverse the position of the truing tool holder 104 on the footstock to the position shown in Fig. 2. One feature of the invention consists in the provision of a truing tool holder so constructed and arranged as to permit it to be located on the center 66 in either of the reverse positions illustrated in Figs. 1 and 2, and in the provision of means cooperating therewith

for shifting the positioning pin 112 from the full line position shown in Fig. 5 to the dot-and-dash position of Fig. 5, so that the truing tool may be supported, and may be given the proper set with relation to the grinding wheel in each of the reverse positions of the footstock as shown in Figs. 1 and 2. The truing tool holder and its adjustable support are constructed and arranged to insure adequate clearance of the supporting parts with relation to the grinding wheel for each of the reverse positions illustrated. To this end the spindle 68 and associated bracket 114 are arranged to be maintained in either of two alternative angular positions which serve to locate the positioning pin 112 equal distances to one side or the other of the axis of the spindle 68 and center 66. The angular position of the footstock spindle 68 is determined by means of a pin 120 which is screw-fitted into the footstock housing, and engages in either of two slots 122, 124 in the external periphery of the spindle 68, as best shown in Figs. 8 and 9.

When the footstock is moved from the position illustrated in Figs. 1 and 5 to 9 inclusive, to the reverse position of Fig. 2, the truing tool holder 104 is first removed, the clamp screw 116 being backed off to release the pin 112 and the clamping screw 110 being similarly backed off to release the holder from the center 66. The screw pin 120 is backed off to permit rotation of the footstock spindle 68 and the truing tool supporting bracket 114 through a small angle to the left from the position of Fig. 5 until the aperture for the positioning pin 112 reaches the dot-and-dash position for the pin 112 designated by the dot-and-dash lines of Fig. 5. The screw pin 120 is now screwed into engagement with the slot 124 (see Fig. 9) thus locking the parts in the alternative angular position. It is also necessary to reset the center 66 with relation to the spindle 68 to bring the flattened portion thereof again into vertical position. In order to apply the truing tool holder 104 to the spindle in its reverse position, it is now necessary only to loosen the set screw 117 and to shift the holder 104 to the opposite end of the pin, which is then fitted into the aperture in the bracket 114. The grinding tool holder is then secured in position by the tightening of the clamping screws 116 and 110.

It will be understood that the invention is not limited to the specific embodiment shown, and that various deviations may be made therefrom without departing from the spirit and scope of the appended claims.

The invention having been described, what is claimed is:

1. In a grinding machine, the combination with a grinding wheel, of a work supporting assembly comprising a work table having a guideway including a pair of positioning surfaces lying in substantially vertical and horizontal planes respectively, a headstock and a footstock each having cooperating vertical and horizontal positioning surfaces and a swivel mounting, and means for securing said swivel mountings under pressure against both of said positioning surfaces on the guideway, headstock and footstock spindles having their axes passing through the axes of said swivel mountings whereby said headstock and footstock are freely interchangeable on said guideway to permit the headstock to be located alternatively at either side of the grinding wheel on the table, and power means for driving the headstock including means for reversing the di-

rection of drive upon shifting from one to the other of said alternative positions.

2. In a grinding machine, the combination with a grinding wheel, of a work support assembly comprising a work table having a guideway thereon including a pair of positioning surfaces lying in substantially vertical and horizontal planes respectively, a headstock and a footstock each having cooperating vertical and horizontal positioning surfaces and a swivel mounting, and means for securing said swivel mountings under pressure against both of said positioning surfaces on the guideway, headstock and footstock spindles having their axes passing through the axes of said swivel mountings whereby said headstock and footstock are freely interchangeable on said guideway to permit the headstock to be located alternatively at either side of the grinding wheel on the table, power means for driving the headstock, and means connectible in shifting the position of the headstock from one side to the other of the grinding wheel to reverse the direction of the headstock drive.

3. In a grinding machine, the combination with a grinding wheel, of a work support assembly comprising a work table having a guideway thereon including a pair of positioning surfaces lying in substantially vertical and horizontal planes respectively, a headstock and a footstock each having cooperating vertical and horizontal positioning surfaces and a swivel mounting, and means for securing each of said swivel mountings under pressure against both of said positioning surfaces on the guideway, headstock and footstock spindles having their axes passing through the axes of said swivel mountings whereby the headstock and footstock are freely interchangeable on the guideway to permit the headstock to be located alternatively at either side of the grinding wheel on the table, an electric motor on the headstock for driving the headstock, and electrical power connections for the headstock motor including a directional electrical outlet adjacent each end of the table, and a plug connection for electrically connecting the motor through one of said outlets in each of said interchangeable positions, said electrical outlets and plug connection cooperating therewith being constructed and arranged to cause the motor to be driven through one outlet in one direction and through the other outlet in the opposite direction.

4. In a grinding machine, the combination with a grinding wheel, of a work supporting assembly comprising a work table having a guideway thereon, a headstock and a footstock interchangeably supported on said guideway to locate the headstock alternatively to opposite sides of the grinding wheel, headstock and footstock spindles, connections including a manual control element for effecting axial movement of the footstock spindle in the footstock, and means in said connections shiftable to locate the manual control element in alternative positions at opposite sides of the footstock.

5. In a footstock, the combination with a swivel mounting, a spindle housing swivelling thereon, and a spindle axially movable in the housing, of means for moving the spindle axially including a manually operable spindle shifting lever, a support for said lever shiftable angularly about the spindle, and means for securing the support in either of two alternative angular positions in which the manual lever is accessible to the operator from one side or the other of the footstock.

6. In a footstock, the combination with a spindle housing and a spindle axially movable therein, of means for moving the spindle axially including a manually operable spindle shifting lever, a sleeve support for said lever shiftable angularly about the spindle, a bearing for the sleeve including means to prevent axial movement of the sleeve support relative to the footstock, and means for securing the sleeve support in either of two alternative positions in which the manual lever is located at one or the other side of the footstock.

7. In a grinding machine, the combination with a grinding wheel, of a work supporting assembly comprising a work table having a guideway thereon, a headstock and a footstock interchangeably supported on said guideway to permit location of the headstock to opposite sides of the grinding wheel, a footstock spindle, a grinding wheel truing tool holder, off-set supporting means for the tool holder on the footstock spindle arranged for supporting the tool holder in alternative positions facing toward one side or the other of the footstock, and means for securing the spindle alternatively in either of two predetermined angular positions to provide identical positions of support for the tool holder facing opposite sides of the footstock.

8. In a grinding machine, the combination with a grinding wheel spindle, of a work supporting assembly including a work table, a headstock and a footstock interchangeably supported on the table, a footstock spindle, a footstock center, a support on the footstock spindle off-set to one side of a vertical plane passing through the axis thereof and including a positioning pin parallel with the spindle axis, a grinding wheel truing tool holder arranged to be supported on the footstock center and positioning pin in alternative positions facing toward one side or the other of the footstock, and means for positioning the spindle in either of two alternative predetermined angular positions in which the positioning pin is off-set on opposite sides of said vertical plane whereby said tool is given the proper set in each of said reverse positions.

9. In a grinding machine, a base, a grinding wheel with supporting means mounted on the base, work supporting and rotating means mounted on the base comprising a table having a guideway thereon and a headstock and a footstock interchangeably supported on said guideway and locatable alternatively on opposite sides of the grinding wheel, headstock and footstock spindles, an electric motor for driving the headstock, and connections for operating the headstock and footstock when positioned on either side of the grinding wheel comprising a directional electrical outlet in the base adjacent each end of the table to cause the headstock to be driven in reverse directions when the headstock is shifted from one side to the other of the grinding wheel and manual control means for the footstock spindle including a lever and an element shiftable to locate the lever in two alternative positions in which it is accessible to the operator from one side or the other of the footstock.

10. In a grinding machine, the combination with a grinding wheel, of a work supporting assembly comprising a work table having a guideway including a pair of positioning surfaces lying in substantially vertical and horizontal planes respectively, a headstock and a footstock each having a swivel mounting, and means for securing said swivel mountings under pressure against both

of said positioning surfaces on the guideway, headstock and footstock spindles having their axes passing through the axes of said swivel mountings whereby said headstock and footstock are freely interchangeable on said guideway to permit the headstock to be located alternatively at either side of the grinding wheel on the table, power means for driving the headstock including means for reversing the direction of drive upon shifting from one to the other of said alternative positions, connections including a manual control element for effecting axial movement of the footstock spindle and the footstock, and means in said connections shiftable to locate the manual control element in alternative positions at opposite sides of the footstock.

11. In a grinding machine, the combination with a grinding wheel, of a work supporting assembly comprising a work table having a guideway including a pair of positioning surfaces lying in substantially vertical and horizontal planes re-

5 spectively, a headstock and a footstock each having a swivel mounting, means for securing said swivel mountings under pressure against both of said positioning surfaces on the guideway, headstock and footstock spindles having their axes passing through the axes of said swivel mountings whereby said headstock and footstock are freely interchangeable on said guideway to permit the headstock to be located alternatively at either side of the grinding wheel on the table, power means for driving the headstock including means for reversing the direction of drive upon shifting from one to the other of said alternative positions, connections including a manual control element for effecting axial movement of the footstock spindle and the footstock, and means in said connections shiftable to locate the manual control element in alternative positions at opposite sides of the footstock.

10 15 MAXWELL I. MATHEWSON.
